Primary Examiner — T Chase Nelson*Assistant Examiner* — Jeff Lenard D Torres(74) Attorney, Agent, or Firm — Ying-Ting Chen; Law Office of Michael Chen(57) CLAIM

The ornamental design for a shoe, as shown and described.

DESCRIPTION

FIG. 1 is a perspective view of a shoe showing my new design;

FIG. 2 is a perspective view thereof from another angle;

FIG. 3 is a right-side elevational view thereof;

FIG. 4 is a left-side elevational view thereof;

FIG. 5 is a rear elevational view thereof;

FIG. 6 is a front elevational view thereof;

FIG. 7 is a top plan view thereof;

FIG. 8 is a bottom plan view thereof; and,

FIG. 9 is a partial enlarged view of the area labeled 9 in FIG. 2.

The dash-dash broken lines in the figure views depict portions of the shoe that form no part of the claimed design. The dot-dash broken lines in FIGS. 2 and 9 show an area of enlargement and the dot-dash lines form no part of the claimed design.

1 Claim, 9 Drawing Sheets
